UNITED STATES PATENT OFFICE.

JAMES H. BOYE, OF CHICAGO, ILLINOIS, ASSIGNOR TO THE BOYE NEEDLE COMPANY, OF CHICAGO, ILLINOIS.

HOLDER FOR PENCILS, PENS, &c.

1,074,927.

Specification of Letters Patent. Patented Oct. 7, 1913.

Application filed November 11, 1912. Serial No. 730,638.

To all whom it may concern:

Be it known that I, JAMES H. BOYE, a citizen of the United States, residing at Chicago, in the county of Cook and State of Illinois, have invented a new and useful Improvement in Holders for Pencils, Pens, &c., of which the following is a specification.

This invention relates particularly to holders for pencils, pens, or the like; and the primary object of the invention is to provide an improved device of the character indicated which may be readily and securely fastened to the clothing in an improved manner.

15 The invention is illustrated in its preferred embodiment in the accompanying drawing, in which—

Figure 1 represents a vertical sectional view of a pencil-holder constructed in accordance with this invention, the view showing, also, in section, a fragment of a vest to which the device is secured; Fig. 2, a front elevational view of the device with the pencil-holder attached; Fig. 3, a rear elevational view of the device; Fig. 4, a sectional view taken as indicated at line 4 of Fig. 2; Fig. 5, a rear view of an improved device in modified form; and Fig. 6, a side elevational view of the device shown in Fig. 30 5, but with the pencil-holding loop indicated by dotted lines.

Referring to Figs. 1 to 4 inclusive, the device, as there shown, comprises a shank or plate 1; prongs 2 secured to the upper portion of the shank 1; and an expansible pencil-holding loop or ring 3 secured to the front side of the shank 1 at the upper end of said shank.

In Fig. 1, the device is shown fastened to a ply of cloth 4, which may constitute the front-piece of a vest, for instance, which is provided with a pocket 5 having a front wall 5^a.

The prongs 2 which lie adjacent the rear surface of the shank 1 are preferably formed integral with each other by bending a wire provided with sharpened extremities into general U-form to provide a web portion 2^a and the depending prongs 2. This U-shaped member has its base or loop end rigidly secured to the upper end of the shank 1. This is preferably accomplished by providing the upper end of the shank 1 with lateral clenching-lugs 1^a and an upper clenching-lug 1^b, which are curved rearwardly and

clenched, respectively, on the upper portions of the prongs 2 and on the web 2^a. The lower end of the shank 1 is curved forwardly, as indicated at 1^c; and above the point of curvature the shank is provided with vertical slots or recesses 1^d. The prongs 2 are provided above their points with forwardly-projecting bends or curvatures 2^d which register with the slots 1^d by which they are received.

The loop 3 which serves to hold the pencil, pen, or the like, may be of any approved construction. In the form shown, it is a tubular member having walls formed of connected, resilient, vertical loops of wire 3^a, this being a well known form of pencil-holding loop. The member 3 is securely attached, in any approved manner, to a short plate or slide 6 which is rigidly secured in a guide-portion 7 with which the shank 1 is equipped on its forward side near its upper end. The shank 1 is also preferably provided below the device 3 with a rearwardly-struck embossment or rib 1^e.

20 In use, the prongs 2 may be thrust through a ply of the user's clothing, and the construction and arrangement are such that the clothing will be firmly gripped between the prongs and the shank 1, thus obviating the danger of loss of the device. This is illus- 80

trated in Fig. 1, which figure also serves to illustrate the convenience with which the device can be located with reference to the pocket 5. The figure shows the device so located that the pencil-holding loop 3 is disposed above the upper margin of the pocket. If desired, the device may be wholly concealed in the pocket, being secured to the rear wall thereof. On the other hand, there is an advantage in locating the projecting loop 3 above the pocket to avoid forming a lump in the pocket. An additional advantage which the improved device possesses is that it overcomes the objection of attaching a device of this character to the front wall 95 of the vest pocket, or to the outer wall of the breast pocket of a coat.

25 In the modification shown in Figs. 5 and 6, the construction is similar to the construction already described. In the modified construction, 1' represents the shank; 2', the prongs; and 3', the pencil-holding loop or circlet. The prongs form a part of a U-shape member whose base portion is secured to the upper end of the shank 1' by a sep- 100

arately-formed metal clip 8. The slots 1 are omitted, and the prongs 2' are provided with outward curvatures 9. That is, the prongs are curved away from each other at the points 9, thus forming enlargements, which, after being forced through the clothing, will serve to prevent the device from becoming accidentally disconnected from the clothing.

10 A device of the character described is simple, cheap, and possesses many advantages in use. The rigid attachment of the U-shaped member to the upper end of the shank or plate of the device renders it possible to apply the device readily to the clothing. Also, the rigid attachment of the U-shaped member and its close proximity to the rear surface of the member 1 insure the gripping of the clothing between the piercing-prongs and shank 1.

15 The foregoing detailed description has been given for clearness of understanding only, and no unnecessary limitation should be understood therefrom.

20 25 What I regard as new, and desire to secure by Letters Patent, is—

1. A device of the character set forth, comprising a shank having a forwardly-curved lower extremity, a pencil-holder attached to said shank near its upper end and projecting in front of said shank, and a pair of piercing-prongs disposed adjacent the rear surface of said shank and having their upper end portions rigidly secured to the upper end portion of said shank, the point-portions of said prongs being separated from the curved extremity of said shank by an acute angle, whereby the device may be readily applied to a garment and may be removed without injury to the garment.

20 40 2. A device of the character set forth, comprising a shank having its lower end curved

forwardly and having its upper portion equipped on its forward side with a pencil-holding loop, a U-shaped member disposed close to the rear surface of said shank and having downwardly-extending sharpened extremities and an upper web portion, and lugs securing the upper portion of said U-shaped member rigidly to the upper portion of said shank, said sharpened extremities being separated from the curved lower end of said shank by an acute angle, whereby the device may be readily applied to a garment and may be removed without injury to the garment.

3. A device of the character set forth, comprising a shank having its upper portion equipped with a pencil-holding member and having its lower extremity curved forwardly, said shank provided above its lower extremity with slots, and a U-shaped member secured at its web portion to the upper end of said shank and affording prongs, said prongs having curvatures engaging in said slots.

4. A device of the character set forth, comprising a shank having its upper portion equipped with a pencil-holding member and having its lower extremity curved forwardly, said shank provided above its lower extremity with a slot, and a piercing-prong disposed against the rear surface of said shank and having its upper portion rigidly secured to the upper portion of said shank, said piercing-prong having a forwardly struck curvature engaging in said slot and having its point portion separated from the curved extremity of said shank by an acute angle.

JAMES H. BOYE.
